UNITED STATES PATENT OFFICE.

JOE VIROVATZ AND JOHN KIRALY, OF ONEIDA, WISCONSIN.

RAIL-FASTENER.

1,132,410.

Specification of Letters Patent. Patented Mar. 16, 1915.

Application filed September 23, 1914. Serial No. 863,150.

To all whom it may concern:

Be it known that we, JOE VIROVATZ and JOHN KIRALY, subjects of the King of Hungary, residing at Oneida, in the county of Outagamie and State of Wisconsin, have invented certain new and useful Improvements in Rail-Fasteners, of which the following is a specification.

This invention relates to certain new and 10 useful improvements in rail fasteners.

The primary object of the invention is to provide a device employable with a railway spike of any desired form for engaging the base flange of a rail and securing the same 15 to the supporting tie, a portion of the device adapted for entering the tie during the driving of the spike into its holding position.

A further object is to provide a removable auxiliary head for a railway spike 20 which is adapted to secure a rail to a supporting tie while a portion of such head is obliquely embedded within the tie and an opposite portion thereof rests upon the base flange of the rail.

With these general objects in view and others that will appear as the nature of the 25 invention is better understood, the same consists in the novel combination and arrangement of parts to be hereinafter more fully 30 described, illustrated in the accompanying drawings and set forth in the appended claim.

In the drawings forming a part of this 35 application and in which like-designating characters refer to corresponding parts throughout the several views, Figure 1 is a view of the device operatively positioned, the tie and rail being shown in vertical section. Fig. 2 is a central transverse sectional

40 view of the device partially broken away and a portion of the spike shown in dotted lines, and Fig. 3 is a perspective view of the auxiliary head detached.

Referring more in detail to the drawings, 45 the invention broadly consists in the provision of an inexpensive means for engaging the base flange 10 of the rail 11 for the purpose of securing the rail to the cross tie 12 and provides an auxiliary head 13 of the 50 form illustrated in Fig. 3 which is slidably mounted upon the railway spike 14 which is of any desired form of retaining spike.

The spike 14 is here illustrated as having 55 a rectangular head 15 with a pointed shank 16 which is rectangular in cross section, while the head has a laterally projecting fin-

ger 17 ordinarily employed for engaging a rail flange, but for use with the present device, the finger 17 performs no function and may be eliminated altogether if desired.

The auxiliary head 13 has a central rectangular bore 18 adapted for the sliding reception of the spike-shank 16 therethrough. At one side of the body portion 19 of the 60 said auxiliary head, a laterally projecting finger 20 is provided having an oblique lower edge 21 adapted to engage the upper surface of the base flange 10 as best illustrated in Fig. 1. An obliquely positioned arm 22, projects from the opposite side of the body 65 portion 19, and has a pointed free end 23, adapted to enter the tie while a plurality of edge-serrations 24 are provided in the arm 22 for engagement with the wooden tie.

With the auxiliary head 13 slidably positioned upon the spike shank 16 and the entire device placed adjacent the rail flange, the spike is driven downwardly in a vertical direction into the tie by the use of force exerted upon the spike head 15, which descent 70 of the spike forces the auxiliary head 13 downwardly, forcing the arm 22 into the tie and the finger 20 into a close engagement with the upper face of the base flange. The 75 rail will thus be firmly secured to the tie and 80 the auxiliary head prevents the spike from accidental loosening during the operating of 85 the railroad.

While the form of the invention herein 90 shown and described is, what is believed to be the preferred embodiment thereof, minor changes may be made without departing from the spirit and scope of the invention as claimed.

What is claimed is:

A device of the class described comprising in combination with a railway spike having a shank rectangular in cross section and a head at one end thereof, an auxiliary head comprising a body portion having a rectangular central bore adapted for the reception of the spike shank slidably therethrough and prevented from relative rotary movement, a laterally projecting finger integrally carried at one side of said body-portion and 100 having a rail-engaging oblique lower face, an obliquely positioned sharpened arm carried by said body-portion at the side thereof opposite to the said finger and adapted for entering engagement with the supporting 105 tie and provided with serrations in its opposite lower edges, the said arm extending 110

below the plane of said body-portion and finger and extending at an angle to the spike shank in assembled position to prevent a direct vertical movement of said auxiliary 5 head and a further outward movement thereof in alinement with the longitudinal axis of the oblique arm.

In testimony whereof we affix our signatures in presence of two witnesses.

JOE VIROVATZ.
JOHN KIRALY.
